UNITED STATES PATENT OFFICE.

BEATRICE C. LUTKINS, OF MONTCLAIR, NEW JERSEY.

DESIGN FOR AN EARRING.

Application filed January 2, 1923. Serial No. 4,800. Term of patent 3½ years.

To all whom it may concern:

Be it known that I, BEATRICE C. LUTKINS, a citizen of the United States, residing at Montclair, in the county of Essex and State of New Jersey, have invented a new, original, and ornamental Design for Earrings, of which the following is a specification, reference being had to the accompanying drawing, forming a part thereof.

The figure is a perspective view of an earring, showing my new design.

I claim:

The ornamental design for an earring, substantially as shown.

BEATRICE C. LUTKINS.
